[57] **CLAIM**

The ornamental design for a combined cervical and head support, as shown and described.

DESCRIPTION

FIG. 1 is a perspective view of a combined cervical and head support showing our new design; the broken line showing is for illustrative purposes only and forms no part of the claimed design;

FIG. 2 is a front elevational view of the back plate portion;
FIG. 3 is a perspective view of a right head support portion;
FIG. 4 is a perspective view of a left head support portion;
FIG. 5 is a front elevational view of a combined cervical and head support;

FIG. 6 is a back elevational view thereof;

FIG. 7 is a right side elevational view thereof;

FIG. 8 is a left side elevational view thereof;

FIG. 9 is a top plan view thereof; and,

FIG. 10 is a bottom plan view thereof.
